J. RUSHING.
MAIL DELIVERY APPARATUS.
APPLICATION FILED MAY 24, 1919.

Patented May 18, 1920.

UNITED STATES PATENT OFFICE.

JOE RUSHING, OF HICKORY RIDGE, ARKANSAS.

MAIL-DELIVERY APPARATUS.

1,340,840.

Specification of Letters Patent.

Patented May 18, 1920.

Application filed May 24, 1919. Serial No. 299,590.

To all whom it may concern:

Be it known that I, JOE RUSHING, citizen of the United States of America, residing at Hickory Ridge, in the county of Cross and 5 State of Arkansas, have invented new and useful Improvements in Mail-Delivery Apparatus, of which the following is a specification.

The object of the invention is to provide 10 simple and efficient means for securing the delivery of mail in sacks or similar packages at predetermined points or stations, from the station to the train, without necessitating the stopping of the latter or the material checking of the movement thereof, and to this end the invention consists in 15 a construction and combination of parts hereinafter set forth, it being understood that changes in form and proportion may 20 be resorted to within the scope of the claim without departing from the principles involved.

In the drawings:

Figure 1 is a plan view of the delivery 25 apparatus.

Fig. 2 is a side view partly in section of the same showing in outline the location of a mail receiving receptacle as carried by a train.

Fig. 3 is a detail view of the train operated trip and related parts.

Fig. 4 is a detail view of the upper end of the casing housing the delivery arm stem.

Located at a selected station or point of 35 delivery of same, and in suitable relation to the line of the railway track indicated in Fig. 1 at 10 is a post consisting in the construction illustrated of a casing 12 in which is mounted a reciprocatory stem 13 with the 40 upper end of which is pivotally connected a supporting arm 14 normally resting upon the lower edge 15 of a bayonet slot 15' formed in the casing. It is thereby held in a substantially horizontal position as indicated in full lines in Fig. 2. This arm is 45 preferably split or bifurcated as shown for engagement with a loop 16 at the upper end of a mail sack 17. The train may be provided with any suitable means for receiving the sack as for example a basket or 50 other receptacle 18 as indicated in Fig. 2, so that while the train is in progress and is passing the station the sack, by the proper manipulation of the supporting means, may 55 be delivered and deposited in said recep-

tacle. The arm 14 when not in use may be swung laterally into the horizontal leg 15" of the bayonet slot, thus placing it in a position parallel with the trap and out of reach of passing trains. In connection with 60 the lower end of said stem 13 there is employed a bell crank lever 19 connected by a rod 20 or its equivalent with a second or intermediate bell crank 21 which in turn is connected by a rod 22 with a bell crank 23 located near one of the track rails 24 as shown in Fig. 3, one arm of the last-named or operating bell crank 23 being arranged in operative relation with a plunger 25 mounted in a suitable guide 26. 70

This plunger is adapted for operation to elevate the stem 13 and thus by permitting the downward swinging movement of the arm 14 to discharge the mail sack, by means carried by the train or the mail car designed for the reception of the mail matter, and to this end said car may be provided with a trip cam supported below the car and in position for engagement with the upper end of the plunger 25 as the train passes 80 the station. In the construction illustrated said trip is provided with a stem 27 mounted in a suitable guide 29 on the car indicated at 30. The trip cam is held normally raised but may be depressed by means of a foot 85 pedal 34 attached to the upper end of the stem 27 to arrange the trip cam in operative relation with the plunger 25.

Obviously when the train approaches a station at which it is desired to collect the 90 mail the trip may be operatively positioned by the mail clerk so that the cam will engage and depress the plunger and thus by elevating the stem 13 cause the disengagement of the mail sack 17 at such time as to 95 cause its reception by the means provided on the mail car for that purpose, such operation being accomplished as will be obvious without necessitating the stopping or material checking of the movement of the 100 train, and hence without the loss of time incident to the collection of mail under the ordinary conditions.

Claimed:

A mail delivery apparatus for railway 105 trains having station mechanism including sack supporting arm, a casing by which the arm is pivotally supported, a stem inclosed by said casing and operatively connected with said arm for causing sack discharging 110

movement thereof, a plunger located adjacent to the tracks, connections between said plunger and said stem whereby depression of the former will cause sack delivery movement of the stem, and train carried mechanism for engagement with said plunger,

said casing being provided with a bayonet guide slot into one leg of which the arm may be swung to throw it out of operative position.

In testimony whereof I affix my signature.

JOE RUSHING.
